UNITED STATES PATENT OFFICE.

JOHN E. HARRIS, OF BURLINGTON, VERMONT.

STAMP HOLDER AND BINDER.

SPECIFICATION forming part of Letters Patent No. 634,454, dated October 10, 1899.

Application filed February 3, 1899. Serial No. 704,356. (No model.)

To all whom it may concern:

Be it known that I, JOHN E. HARRIS, a citizen of the United States, residing at Burlington, in the county of Chittenden and State of 5 Vermont, have invented and produced a new and useful Stamp Holder and Binder; and I do declare the following to be a full, clear, and exact description of the same.

The objects of this invention are, first, to 10 provide means for the sale and delivery of postage and other adhesive stamps in such a condition that they may be carried into tropical countries and other warm moist places without injury, and, second, to provide a system 15 of binding therefor which shall require no special printing of stamps for the purpose and requiring very little skill or expense in its manipulation.

The difficulty to overcome in this matter 20 was the absence of suitable margins at convenient places in a sheet of printed stamps to provide means for binding the same in book form. In other words, should the Government be willing to provide (during the operation 25 of printing stamps) blank spaces in each sheet of stamps, which blank portion of the sheet might be used between other sheets or cover margins to form a book of convenient shape and size to meet the wants of the purchaser, then there would exist no real difficulty 30 in serving the public with these adhesive stamps in otherwise than perishable condition; but as such an undertaking on the part of the Government would entail very great confusion and loss of material composing 35 the sheets upon which the printing is done, with a view to making the most stamps that is possible from a sheet, it would not be found practicable to introduce such a custom in any country. To overcome the difficulty here manifested, I have invented this system of 40 binding, through which fractional portions of the regular sheets of postage, revenue, and other like perforated (edged) stamps, when gummed or otherwise may be bound and held, so as to meet all practical requirements of the case, and I will now proceed to describe the 45 same with reference to the accompanying drawings, which form a part of this specification, and in which—

Figure 1 represents a plan or inner face view of a prepared card or other sheet of suit-

able material preparatory to being folded, as hereinafter shown, to hold a given number of stamps, as herein represented. Fig. 2 represents in perspective one of the sheets of stamps calculated to be fitted for use in one of the spaces marked A B C. A plan of this sheet is shown in Fig. 1 of my drawings. Fig. 3 represents an end view of two prepared 60 blank cards or sheets so folded as to form three spaces for the reception of as many full sheets of stamps. (Shown in dotted lines). Fig. 4 shows an arrangement of two elastic bands or cords for binding sheets of stamps 65 and other material together, as hereinafter set forth. Fig. 5 represents an end view of folded cards or sheets held together by means of the elastic device shown in Fig. 4 of the drawings.

Embraced in the essential features of the 70 invention is the odd arrangement of the stamps in the book, whereby the solid center of one or more of the stamps is made to occupy the central position where the bending takes place, coincident with the bending of the 75 cover, which cover is provided with notches D and E, as shown, for the reception of an elastic band or its equivalent F, which band passes over the face of the central stamps on the one side and over the back of the cover on the 80 other, thus binding the stamps to the cover whether the same are in an open or closed condition. The cover in this case (marked G) is simply one of the stiff folders prepared with oil or other material to prevent the 85 gummed side of the stamps from sticking to its surfaces under any natural conditions, which folders may be used inside of one another to a considerable number with good effect; but I shall confine myself here to the description of two in combination. When the 90 six inner faces of these two folders are duly treated, the gummed side of the stamps may be laid against them, leaving the face of the stamps in such position as to meet when folded 95 in each space left for their reception, wherefrom all other operations connected with the device may be carried out with perfect ease.

In will be observed in Fig. 3 that a single band or cord is used for the purpose of binding both folders G and H, together with their contained sheets of stamps, (shown in dotted lines,) two sheets of the same being held entirely between the inner surface of the former

and outer surface of the latter. As a modification of this device, Fig. 5 provides for receiving separate folds of the stamp sheets between each of the spaces therein formed by 5 the folders G and H and which is accomplished through the use of two bands or cords K and L, one of which, K, binds the folders, as in Fig. 3, while the other, L, passes over K at both ends and also passes through the 10 space formed between G and H and incidentally through the fold of the stamp sheet when there in place, here shown elevated in dotted lines to avoid confusion.

While this device may be of any suitable 15 dimensions and to contain stamps of great variety, I have here illustrated and shown a book of three double pages, each containing twenty stamps or, say, forty two-cent and twenty one-cent stamps, or one dollar's worth 20 in denominations such as will admit of many useful combinations for postal charges. Furthermore, while this division furnishes the requisite odd arrangement across the face of the book, as described, it uses up an ordinary 25 sheet of printed stamps without a remnant—that is to say, there are in practice four hundred stamps printed on one sheet, or twenty stamps in both directions—wherefore this economic calculation in connection with the other 30 practical requirements in this case, which admits, further, of introducing printed folders

for giving postal and other information and which could be bound in separately (if need be) at little cost, as the same elastic band or cord which is used for holding the other parts 35 together would serve as a binder for auxiliary sheets whether placed on the inner or outer side of the original folded sheets of the device.

Having thus described my invention, what I here claim, and desire to secure by Letters 40 Patent of the United States, is—

In a device for holding and binding postage and other stamps, the combination of two folded sheets of material notched at the top and bottom as shown, with two elastic bands 45 or cords, one of which passes over the center of the inner sheet and over the outer surface of the outer sheet, after passing through the notches at the top and bottom, while the other band or cord is passed over the ends of the 50 inner sheet and band and through the spaces formed between the two sheets as shown, for the purpose of holding separately the folds of stamp sheets introduced in these outer spaces as described. 55

In testimony whereof I hereunto set my hand in presence of two witnesses.

JOHN E. HARRIS.
